TRACK ROLLER SEAL CONSTRUCTION

David B. Baker, Riverside, Clifford E. Rogers, Oak Park, and William O. Bechman, Chicago, Ill., assignors to International Harvester Company, a corporation of New Jersey

Application March 5, 1937, Serial No. 129,168

3 Claims. (Cl. 286—5)

This invention relates to the construction of track rollers or the like utilized in crawler tractors to transmit the weight of the tractor to the ground run of the endless tractor belt. More particularly, the invention relates to a seal mechanism disposed between respective ends of the track roller and the shaft on which the roller turns, to insure that dirt and dust from the outside cannot find ingress to the bearing surfaces on which the roller turns, and that oil from within the roller, that lubricates the bearing surfaces, cannot seep out. The fact that these track rollers are under heavy load makes it necessary that the bearing surfaces on which the roller turns be properly lubricated and protected from wear caused by the entry of extraneous abrasive matter.

The object of the invention is the provision of a track roller structure with seals effective to retain oil within the structure and to keep dirt from entering.

These track rollers are carried on a stationary shaft and secured horizontally between the sides of a so-called track roller frame by means of brackets which serve to fix the shaft in the frame. The improved seal structure of this invention is arranged between the respective ends of the roller and the adjacent end of said bracket, as will hereinafter appear.

The improved track roller seal construction is shown in the accompanying sheet of drawings, wherein:

Figure 1 is a cross-sectional view through so much of the track roller and the support structure therefor as is necessary to disclose the invention; and,

Figure 2 is a similar cross-sectional view fragmentarily showing a modified form of seal.

In the track roller construction there is utilized a track roller frame 10 having opposite side channel members 11, only one of which is shown. A round shaft 12 is horizontally disposed and has reduced ends 13 semicircularly shaped with an upper flat edge 14 that is placed flatly under the lower flange of the frame channel 11. A bracket 15 including a bolt 16 is used to rigidly clamp the reduced semicircular end 13 of the shaft 12 to the under side of the lower flange of the channel frame member 11. In this fashion the shaft 12 is held stationary in the frame 11. This shaft, midway between its ends, is formed with an upset radial flange 17, and the shaft is formed with a central bore 18 including a radial bore 19, which extends vertically upward through the flange 17, as shown. One

end of the passage 18 carries a fitting 20 whereby suitable lubricant may be forced into the bore 18 of the shaft to load the same with lubricant, as will later appear. Radial passages 21 from the passage 18 are also provided in the shaft 12. 5

The bracket 15 is carried below the frame 11 and includes an annular channel-shaped rim portion 22 and around the shaft 12 in spaced relation thereto. Surrounding the shaft 12 on each side of the flange 17 are bearings 23, and 10 disposed on these bearings are carriers 24, which are circular, and to the outer periphery of which are tightly fitted, as by shrinking thereon, the track roller 25, a snap ring 26 being provided to hold the roller 25 and carrier 24 against relative axial shifting movement. It will be noted that the outer face of the carrier 24 is provided with an annular passage or reentrant portion 26', which telescopically fits over the channel-shaped rim 22 of the bracket 15. The fit of the 20 rim 22 within the portion 26 is sufficiently close though without contact and the overlap of the parts is considerable so that there is a running tolerance seal formed at this point even without the aid of other seals. A pack of flat felt, or 25 other fiber, washers 27 is located between the outer side of the passage 26' and the inner adjacent side of the channel rim 22. It will be noted that the carrier 24 has an axial extension 28 which forms a channel-shaped 30 annular space 29 in which is placed another pack of felt or the like washers 30, said washers being located within the inner diameter channel of the rim 22 and around the hub portion 28 of the carrier 24. At the outer edge of the annular 35 hub portion 28 and the adjacent inner face of the bracket 15 is another pack of flat fiber or felt washers 31. Between the rim portion 28 and the shaft 12, the carrier 24 provides an annular passage 32 surrounding the shaft, in which 40 is located another seal 33 of the unitary type, which includes an annular leather 34 and a second annular leather 35, these leathers constituting seal elements flexibly engaging the periphery of the shaft 12. 45

In Figure 2, a slight modification of the seal structure is shown in that the laminated felt washer seal pack 31 is shown at 31' and its outer diameter is retained by a channel-shaped metallic rim 36, which is L-shaped in cross-section, 50 as shown, better to locate the said laminated fiber washer pack 31'. It will be noted in Figure 2 that all of the other parts correspond identically with the showing in Figure 1, and the same ref- 55

erence characters have been used with the addition of an exponential prime.

The opposite side of the track roller construction is the same as that shown in the drawing, as will, of course, be understood. By means of a grease gun, or the like, the nipple 20 is used to load the passage 18 with oil, which also is forced up the passage 19 and into the space between the opposite two carriers 24 inside the roller 25. This oil passes by gravity to the thrust surface on the flange 17, against which the inner ends of the two opposite carriers 24 abut, and also by means of the radial passages 21 it passes by gravity to the needle bearings 23 to lubricate this bearing surface. The oil, if it is to seep out, must pass the two leathers 34 and 35 of the double rawhide seal unit 33, and thence past the laminated felt or fiber seal pack 31 or 31'. Dust cannot get into the bearings 23 without having to pass from the outside into the space 26' and past the fiber pack 21, and then past the tortuous passage formed by the channel rim 22 or 22', and then past the fiber pack 30 or 30', as well as the fiber pack 31 or 31'.

It can now be seen that an improved seal structure has been provided for track rollers and the like of the type described which achieves the object of keeping the oil in and dirt out, thereby serving to cause the roller to operate efficiently and have a long and satisfactory life.

It is the intention to cover herein all changes and modifications of the example of the invention herein shown for purposes of illustration which do not in material respects constitute departures from the spirit and scope of the invention.

What is claimed is:

1. In combination, a stationary shaft, a first member secured to the shaft, said member including an annular part provided with a channel on the inner surface thereof, a second rotatable

member journaled on the shaft, said rotatable member having its end face adjacent the first member formed with a reentrant groove into which the annular part of the first member extends so as substantially to form an enclosed space, a seal in the space, said rotatable member on the same face also having a hub portion spanning the channel on the inner surface of the annular part, and a seal in the channel of the annular part surrounding the hub portion.

2. In a construction comprising a stationary shaft, a stationary member surrounding the shaft, and a rotatable member journaled on the shaft, the combination with a portion of the rotatable member having a reentrant groove in the side thereof, of a portion of the stationary member of substantially the width of and fitting into the reentrant groove in the rotatable member so as to form an enclosed space, and a seal within said space.

3. In combination, a stationary shaft, a first member secured to the shaft and including an annular part provided with a channel on the inner surface thereof, a second rotatable member journaled on the shaft, having a portion fitting within the annular part of the first member so that the channel in the annular part and the portion of the rotatable member form an enclosed space, a seal in the space, said rotatable member also having a reentrant groove in the side thereof into which the annular part extends so as to form an enclosed space, and a seal in the space, the fit of the annular portion of the stationary member within the reentrant groove being sufficiently close and the overlap of the parts being considerable so as to provide a running tolerance seal.
